UNITED STATES PATENT OFFICE.

ERNEST E. SWEET, OF DETROIT, MICHIGAN, ASSIGNOR TO CADILLAC MOTOR CAR COMPANY, OF DETROIT, MICHIGAN, A CORPORATION OF MICHIGAN.

WORM-GEARING.

No. 893,032.

Specification of Letters Patent. Patented July 14, 1908.

Application filed January 11, 1908. Serial No. 410,439.

To all whom it may concern:

Be it known that I, ERNEST E. SWEET, a citizen of the United States of America, residing at Detroit, in the county of Wayne 5 and State of Michigan, have invented certain new and useful Improvements in Worm-Gearing, of which the following is a specification, reference being had therein to the accompanying drawings.

10 The invention relates to that type of steering gear in which rotation of the steering wheel and stem is transmitted through the medium of a gear to a transversely-extending rock shaft, and from the latter to the mechanism for turning the wheels. In order that the vehicle may be turned in a small space, it is necessary to provide a gear segment which may be adjusted through a relatively large angle but in the ordinary 15 operation of the apparatus, where the vehicle is merely guided in a substantially straight course, the angular movement imparted to the gear is very slight. As a consequence, the wear in the gear teeth is chiefly limited to 20 the central portion of the segment, and it is in this portion that it is most desirable to take up all lost motion, so that the vehicle will respond quickly to any movement of the steering wheel. Adjustment for taking up 25 the lost motion is a simple matter, merely requiring the movement of the shaft on which the gear segment is mounted towards the axis of the coöperating gear member, but it is obvious that if such adjustment is 30 made, to take up wear, limited to the central portion of the gear segment, it will cause the binding of the teeth on opposite sides of this central portion when the gear is moved through a greater angle, thus rendering the 35 gear practically inoperative. The present invention is designed to overcome this difficulty by providing a construction in which adjustment may be made to compensate for wear in the central portion of the gear without 40 interfering with the operativeness of the apparatus when moved through a greater angle.

To this end the invention consists in a construction of worm gear which initially is 45 provided with a slight clearance for the teeth of the outer portions of the segment when the axis of the gear shaft is properly adjusted to take up all lost motion in the central portion of the segment. With such 50 a construction, when the central portion of

the segment wears, the gear may be adjusted without producing any binding effect on the teeth of the outer portions of the segment.

In the drawings—Figure 1 is a vertical section through a steering gear to which my improvement is applied; Fig. 2 is an elevation of the worm gear illustrating the principle of construction thereof; and Figs. 3 and 4 are similar views illustrating modifications.

A is the rotary steering stem and B is the worm member mounted upon this stem and preferably within a suitable housing C.

D is the worm gear, which is mounted upon the rock shaft E, and the latter is adjustably mounted in the casing preferably by being journaled in eccentric bearings F therein. In the cutting of the teeth on the gear segment D, instead of adjusting the center of rotation to coincide with the axis G of the rock shaft E, it is adjusted to turn from a center H upon a slightly lesser radius. This will result in providing a slight clearance for the teeth at opposite ends of the segment D which gradually diminishes as the center of the segment is approached, and thus the required adjustment for wear in the central portion of the segment is at any time permissible.

With the construction described, adjustment may be made by any user of the machine without requiring the exercise of special mechanical skill. Furthermore, the wear in the gear tends to render it more rather than less perfect for it enlarges the segment in which the teeth are in full mesh. The slight play between the teeth at the ends of the segment and the worm is immaterial for these parts are only in engagement when the steering wheels of the vehicle are turned at a decided angle, and at such times the resistance of the wheels will keep the worm and gear in contact. On the other hand, where there is any play at the center of the gear there will be constant vibration and rattling, as there is no resisting force to hold the parts in contact.

The adjustments which are provided in steering gears not constructed in accordance with my invention are only serviceable for factory adjustment—that is, for originally setting the gears in proper place before they have been in use, but after wear such adjustments cannot be used for the reasons already set forth.

In Figs. 3 and 4 modified constructions are illustrated, the former showing a pinion I engaging a rack J, the teeth of which are slightly deflected from a straight line. In Fig. 4 a segmental rack, similar to that illustrated in Fig. 2, is employed, but is arranged to engage a straight gear or pinion K, instead of the worm gear. Both of these constructions embody the same principle as the constructions illustrated in Figs. 1 and 2, viz, that the central portion of the rack has its teeth slightly in advance of the end portions thereof.

While the present construction is especially adapted for the steering mechanism of motor vehicles, it is not, however, necessarily limited to such a combination, as it will be observed that it can readily be adapted for various uses in other gear constructions, and also that the design and construction of the gearing may be varied without departing from my invention.

What I claim as my invention is:

1. In a gearing, coöperating intermeshing members constructed to provide a slight clearance between the intermeshing portions thereof when moved from the normal position, while being in full engagement at the normal position.
2. In a gearing, coöperating intermeshing members constructed to provide a slight clearance when moved in either direction

from the normal position while being in full engagement at the central or normal position.

35

3. In a gearing, coöperating gear members, the pitch line of the teeth of one of said members having a different radius than the axis of rotation of said gear, for the purpose described.

40

4. A worm gearing, the pitch line of the teeth of the gear member thereof having a different radius than the axis of rotation of said gear, for the purpose described.

45

5. In a gearing, coöperating intermeshing members constructed to provide a slight clearance between the intermeshing portions thereof when moved from the normal position, while being in full engagement at the normal position, and means for adjusting 50 the relation of said coöperating members.

6. In a gearing, coöperating gear members, the pitch line of the teeth of one of said members having a different radius than the axis of rotation of said gear, and means for 55 adjusting the relation of the centers of said radii, for the purpose described.

In testimony whereof I affix my signature in presence of two witnesses.

ERNEST E. SWEET.
